UNITED STATES PATENT OFFICE.

FRED C. THOMPSON, OF BURTON, WASHINGTON.

POWER-TRANSMITTER FOR WINDMILLS.

SPECIFICATION forming part of Letters Patent No. 642,936, dated February 6, 1900.

Application filed April 8, 1899. Serial No. 712,272. (No model.)

To all whom it may concern:

Be it known that I, FRED C. THOMPSON, of Burton, in the county of King and State of Washington, have invented a new and Improved Power-Transmitter for Windmills, of which the following is a full, clear, and exact description.

The object of the invention is to provide a new and improved power-transmitter for windmills arranged to insure a proper transmission of the power of a wind-wheel to the main shaft both in light and strong winds.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the views.

Figure 1 is a sectional side elevation of the improvement. Fig. 2 is a transverse section of the same on the line 2 2 in Fig. 1. Fig. 3 is a face view of the transmitting-gearing 25 with parts in section, and Fig. 4 is a plan view of part of the improvement with parts in section.

A wind-wheel A of any approved construction is mounted with its hub A' to rotate 30 loosely on the main shaft B, journaled in suitable bearings in a head C, mounted to turn on the upper end of a post or tower D. On the face of the web A², extending from the hub A' to the rim A³ for attaching the wings of 35 the wind-wheel, is arranged a centrifugal governor consisting of levers E, preferably two in number and each fulcrumed at E' on said web A². Each lever E is connected by a link E² with a resistance-arm E³, mounted 40 to rotate loosely on the hub A' and pressed on by a spring E⁴, coiled on the hub A' and secured with one end to the said resistance-arm E³ and with its other end to a collar E⁵, attached to the said hub A'. The resistance-arm E³ is pivotally connected with a rod E⁶, 45 fitted to slide loosely in a guideway F, fulcrumed on an arm F', secured on a shaft F², journaled in the web A². On the rod E⁶ are secured spaced pins E⁷ and E⁸, adapted to pass 50 through slots in the guideway-bearings for the rod to engage and press against collars E⁹ and E¹⁰, respectively held loosely on the rod E⁶ be-

tween the guideway-bearings and pressed on by the ends of a spring E¹¹, coiled loosely on the rod E⁶. This arrangement forms a counter-balance for the governor, as the spring E¹¹ offers a desired resistance to the rod E⁶, the resistance-arm E³, and the governor-levers whether the latter swing outward or inward. The resistance-arm E³ is normally held in the 55 position shown in the drawings by the action of the spring E⁴, which is compressed by the arm when the latter is turned in one direction by the outward-swinging levers E, caused by centrifugal force. When the wheel A attains 60 a very high velocity, so that it runs above a normal speed, then the levers E fly outward and turn the resistance-arm E³ to such an extent that the guideway is shifted and a turning motion is given to the shaft F² by the 65 arm F'.

On the shaft F² is secured a pawl F³, normally in mesh with a ratchet-wheel H, (see Fig. 2,) and on the said shaft is secured a second arm F⁴, connected by a link F⁵ with an 70 arm F⁶ on a shaft F⁷, likewise journaled in the web A², diametrically opposite the shaft F². On the shaft F⁷ is secured a pawl F⁸, likewise normally in mesh with the ratchet-wheel H. When the shaft F² is turned as 75 above described, the pawls F³ and F⁸ are simultaneously swung out of mesh with the ratchet-wheel H and in mesh with the smaller ratchet-wheel G. (See Fig. 3.)

The ratchet-wheel G has its hub G' mounted 80 to rotate loosely on the hub A', and the ratchet-wheel H has its hub H' mounted to rotate loosely on the hub G', and on said hubs G' H' are secured gear-wheels G² H², respectively, 85 in mesh with gear-wheels I J, respectively, 90 of which there are preferably two sets, the two gear-wheels in each set being fastened together and mounted to turn on a stud K', projecting from an arm K, attached to the main shaft B. The gear-wheels I are in mesh 95 with an annular rack L, secured to or forming part of the head C, so that said gear-wheels I roll off on the annular rack.

When the wind-wheel A rotates at a low or normal rate of speed, then the resistance-arm E³ holds the governor-levers E in the normal position above referred to and shown in Figs. 1 and 2, so that the pawls F³ and F⁸ remain in mesh with the ratchet-wheel H,

and consequently the rotary motion of the wheel A is transmitted by the pawls F³ F⁸, ratchet-wheel H, and gear-wheel H² to the gear-wheels J to rotate the same and to cause the gear-wheels I to roll off on the fixed annular rack L, so that the arm K is turned, and consequently the shaft B is revolved. When the speed of the wind-wheel A increases, then the governor-levers E finally fly outward, as before explained, and swing the pawls F³ F⁸ out of mesh with the ratchet-wheel H and into mesh with the smaller ratchet-wheel G, so that the rotary motion of the wheel A is now transmitted by the pawls F³ F⁸, the ratchet-wheel G, and the gear-wheel G² to the gear-wheels I, and as the latter roll off on the fixed internal gear-wheel L it is evident that the arm K is swung around and the main shaft B is rotated.

From the foregoing it is understood that the annular rack L, the gear-wheels I J G² H², the arm K, the ratchet-wheels G H, and the pawls F³ F⁸ form a differential gear which connects the main or power shaft B with the wind-wheel A, and this differential gear is connected with and controlled by the centrifugal governor carried by the wind-wheel A.

The differential gearing above described and as shown in the drawings is so proportioned that when the wheel A rotates at a minimum speed then six revolutions of the wheel A are required for one revolution of the shaft B, and when the wheel A rotates at a high rate of speed then four revolutions of the wind-wheel will produce one revolution of the shaft B.

It is evident from the foregoing that a proper transmission of the power of the wind-wheel takes place both in light and strong winds.

In order to protect the governor mechanism and the transmitting-gearing described, a rim A³ is preferably extended over part of the external surface of the stationary annular rack L, and a hood A⁴, of sheet-iron or like material, is secured to the rim A³ and extended to the outer end of the hub, as will be readily understood by reference to Fig. 1. The web A² of the wind-wheel A is provided with an offset, into which extend the ratchet-wheels H and G and the pawls F³ F⁸ of the differential gear, and the rear portion of the hub A' is reduced in thickness by an amount equal to the thickness of the hub G' of the ratchet-wheel G¹¹.

The main shaft B is provided at the head C with two crank-arms B' B², standing in opposite directions to each other and connected by pitmen N N', respectively, with arms N² N³, fulcrumed on a shaft N⁴, carried by a bracket C', attached to the head C. The arms N² N³ are connected with pump-rods N⁵ N⁶, respectively, extending through the main hollow portion of the head C and through the tower D to connect with pumping machinery in the usual manner.

The frame O for the vane is pivoted on the

head C and is normally held to the wind by a spring O', said frame being pivotally connected by a link O² with an arm P, secured on a shaft P', mounted to turn in suitable bearings in the bracket C'. On the shaft P' is attached a segment Q, to which is fastened a chain R, extending through the hollow portion of the head C and the tower D to the ground to be within reach of the operator to allow of pulling said chain and turning the segment Q and shaft P' to bring the frame O, with the vane, out of the wind by the action of the arm P and link O² on said frame O.

When it is desired to bring the vane into the wind, the operator releases the chain R to permit the spring O' to return the vane-frame and its vane to their normal positions, the pivotal end of the frame abutting against a flat spring O³, attached to the head C.

From the foregoing it will be seen that the power given to the shaft B is transmitted by the oppositely-arranged crank-arms B' B² to the pump-rods to move the latter alternately in opposite directions, so as to insure a continuous pumping. It will further be seen that by the arrangement described the operator is enabled to conveniently throw the wind-wheel out of the wind whenever it is desired to do so.

Having thus fully described my invention, I claim as new and desire to secure by Letters Patent—

1. A power-transmitter for windmills, comprising a revoluble wind-wheel, a main shaft, a centrifugal governor carried by said wind-wheel, and a differential gear connecting said main shaft with said wind-wheel, and connected with and controlled by the said governor, substantially as shown and described.

2. A power-transmitter for windmills, comprising a revoluble wind-wheel, a shaft on which the wheel is mounted to turn loosely, independent ratchet-wheels mounted to rotate loosely, a centrifugal governor on said wind-wheel, pawls controlled by said governor and adapted to engage either of said ratchet-wheels, and planetary gearing driven from said ratchet-wheels and connected with said shaft, substantially as shown and described.

3. A power-transmitter for windmills, comprising a wind-wheel, a main shaft on which the said wind-wheel is mounted to rotate loosely, a governor actuated from the said wind-wheel, and a differential gear connecting the said main shaft with the said wind-wheel and connected with and controlled by the said governor, substantially as shown and described.

4. A power-transmitter for windmills, provided with a revoluble wind-wheel, a governor actuated from the said wind-wheel, pawls controlled by the said governor and carried by said wind-wheel, independent ratchet-wheels adapted to be engaged by said pawls to transmit the rotary motion of said wind-wheel to either of the said ratchet-wheels according to the speed of the wind-wheel, a main

shaft, and an intermediate mechanism between the said ratchet-wheels and the said main shaft to rotate the latter from the ratchet-wheel rotated at the time, substantially as shown and described.

5. A power-transmitter for windmills, provided with a revolute wind-wheel, a main shaft, centrifugal levers carried by said wind-wheel, a spring-pressed resistance-arm for 10 said centrifugal levers, pawls connected with the said resistance-arm, independent ratchet-wheels adapted to be engaged by said pawls to transmit the rotary motion of the said wheel to either of the said ratchet-wheels according 15 to the speed of the wind-wheel, and intermediate mechanism between the said ratchet-wheels and the said main shaft to rotate the latter from the ratchet-wheel rotated at the time, substantially as shown and described.
- 20 6. A power-transmitter for windmills, com-

prising a revolute wind-wheel, a main shaft, a centrifugal governor carried by said wind-wheel, a differential gear connecting said main shaft with said wind-wheel, and connected with and controlled by said governor, the 25 said differential gear comprising independent ratchet-wheels, gear-wheels secured to the ratchet-wheels, a pair of gear-wheels in mesh with the ratchet-wheel gear-wheels, an arm secured to the said main shaft, an annular 30 rack with which one of the said pair of gear-wheels is in mesh, and pawls carried by the said wind-wheel and connected with the said governor and adapted to engage either of the said ratchet-wheels, substantially as shown 35 and described.
